Application March 23, 1946, Serial No. 656,712

8 Claims. (Cl. 103—46)

1

My invention relates primarily to fluid operated pumps and, more particularly, to such a pump having a novel piston construction.

In the oil industry it is common practice to use a fluid operated pump in pumping oil from a well, such a pump generally comprising a coupled motor and pump combination set in the well at the level from which it is desired to pump the oil. In such a pumping device, the motor is normally actuated by admitting operating fluid, such as oil, under relatively high pressure alternately to opposite ends of a motor piston to reciprocate the same, the reciprocation of the motor piston being suitably communicated to a pump piston in the pump end of the device so as to pump oil from the well. In order to conduct operating fluid alternately to opposite ends of the motor piston, a suitable valve mechanism is employed. The valve mechanism may be similar to that disclosed in my Patent No. 2,134,174, issued October 25, 1938, although I prefer to employ my present invention in connection with a governing valve mechanism such as that disclosed in my Patent No. 2,311,157, issued February 16, 1943. However, it will be understood that my present invention may be employed in connection with any suitable valve mechanism other than those mentioned and, if desired, may also be employed in many installations independently of any such valve mechanism.

An object of my invention is to provide a shock absorbing or cushioning piston which may either be employed as the motor piston or as the pump piston of such a pumping structure to reduce the large accelerations frequently resulting from rapidly varying loads on the pumping structure. The alternate application of pressure to the opposite ends of the motor piston, through a suitable valve mechanism produces controlled acceleration, at the beginning of each stroke, of the moving elements of the pump structure and the fluid column which is being lifted. The forces resulting from these accelerations at the ends of the stroke are ordinarily quite small as compared to the forces resulting from the high deceleration of the moving system and the operation fluid column and acceleration of the pumped fluid column which may occur at some intermediate point in the stroke if the fluid being pumped contains free gas.

In pumping oil from a well, the well oil frequently contains mixed therewith or in solution therein varying quantities of natural gas produced from the well together with the oil, the quantity of such gas depending upon the amount

2

of gas in the producing formation with the oil and the bottom hole conditions of temperature, pressure, mechanical agitation, etc. Furthermore, it is common experience in the oil industry that the quantity of gas in the oil entering the pump in a particular well frequently varies within wide limits at different times during production from the well. Since displacement type pumps are most commonly used to pump oil, considerable difficulty has been experienced, with gas being released within the pump cylinder due to agitation and pressure drop through the intake valves and passages, thus reducing materially the pumping load until the pump piston compresses this gas and strikes solid well fluid in the pump cylinder. Similar pumping load decreases may result from operating the pump with the pump intake valve plugged, or from operating the pump beyond the fluid capacity of the well so that gas is present in the pump cylinder.

In fluid operated pumps, if the pumping load on the pump piston decreases for any of the reasons mentioned above, or for any other reason, the entire pumping mechanism tends to accelerate very rapidly until the pump piston strikes solid well fluid in the pump cylinder.

This acceleration may continue until the piston velocity greatly exceeds that corresponding to the rate of supply of the operating fluid. This results from the fact that this operating fluid has an appreciable compressibility at the required operating pressure and the volume of operating fluid contained in the power oil tubing is large. When the pump load decreases for any reason the operating fluid expands driving the piston ahead at a high speed limited only by the friction losses in the tubing and fluid passages in the engine. To visualize the amount of this expansion assume an 8,000 ft. well with an operating pressure 3,000 pounds per square inch. At this pressure the power fluid is compressed 1.5%, or 120 feet expressed as length of fluid column. The area of the inside diameter of the power tubing is approximately equal to that of the engine piston so the engine piston would travel 120 feet before the power fluid in the system would be expanded to 0 pounds per square inch. The stroke of the piston may be 2 feet so that at the end of the first stroke the pressure would be reduced to only 2950 pounds per square inch. Therefore, during the first stroke the average pressure which would have to be consumed in friction would be 2950 pounds per square inch. The resulting velocity to develop this friction loss might drive the piston at 5 to 10 times the maximum rated speed.

When the pump station piston hits the well fluid, the entire pumping mechanism decelerates substantially instantaneously to almost zero speed and then accelerates again until the well fluid in the tubing is brought up to normal speed. Such negative accelerations or decelerations may be of extremely large magnitude and introduce hydraulic shock loads which result in abnormal stressing of the parts of the pumping mechanism and which may cause considerable damage in the form of excessive wear, scoring, seizing, or even breakage of the parts. By employing my shock absorbing piston as either the motor piston or the pump piston, the magnitudes of such decelerations are greatly reduced to minimize hydraulic shock loads on the pumping structure by distributing the deceleration and acceleration of well fluid over longer periods of time, thus providing for more uniform operation of the pumping mechanism.

A further object of the invention is to provide in such a fluid operated pump a piston which is loosely connected to its piston rods so that the piston will be self-aligning between the rods and the bore of the cylinder in which it reciprocates. This feature eliminates the necessity of working to close tolerances in maintaining accurate concentricities of the parts.

Other objects and advantages will appear from the following specification and the drawings, which are for the purpose of illustration only, and in which:

Fig. 1 is a vertical sectional view showing a fluid operated pump including my invention as installed in a well;

Fig. 2 is an enlarged vertical sectional view showing the motor section of the pump illustrated in Fig. 1;

Fig. 3 is a vertical sectional view showing the pump section of the invention and is a downward extension of Fig. 2;

Fig. 4 is a vertical sectional view showing the lower end of the pump and is a downward extension of Fig. 3;

Fig. 5 is a further enlarged vertical sectional view of the motor piston assembly shown in Fig. 2; and

Fig. 6 is a graph illustrating the operation of the invention.

Referring particularly to Fig. 1, I show a well casing 11 which extends downwardly from a casing head 12 into the oil producing formation of a well, the lower end of the casing being provided with conventional perforations 11a. From a fitting 13 forming an intermediate part of the casing head 12, a production tubing 14 extends downwardly through the casing 11 into a body of oil 15 in the lower portion thereof. The lower end of the production tubing 14 is equipped with a pump seat 16 adapted to receive and support the lower inlet end 17 of a fluid operated pump 18. A power tubing 19 extends downwardly through the production tubing 14 and has its upper end connected to a cap member 20 of the casing head 12, the lower end of the tubing 19 being connected to the pump 18.

The pump 18 comprises a lower pump section 21 and an upper motor section 22, best shown in Fig. 2, including a motor cylinder 23, the lower end of which is connected to a pump cylinder 25, best shown in Fig. 3. The motor cylinder 23 is provided with a cylinder liner 27 therein, there being longitudinal passages 28 therebetween, the liner having a bore 29 in which is provided a reciprocable motor piston assembly 30.

The motor section 22 is provided near its lower end with ports 32 which communicate between the passages 28 and the bore 29 adjacent the lower end of the bore. The upper end of the bore 29 communicates through ports 33 with a passage 34. The passages 28 and 34 extend upwardly to a valve mechanism (not shown) which is adapted to introduce operating fluid from the power tubing 19 alternately into the passages 28 and 34 and thus alternately into the bore 29 at opposite ends of the motor piston 30 to reciprocate the piston, the motor piston being connected to the valve mechanism by an upper pilot rod 35. As previously mentioned, the valve mechanism may be of any suitable construction such as that disclosed in my aforesaid Patent No. 2,134,174, although I prefer to employ the governing valve mechanism disclosed in my aforesaid Patent No. 2,311,157.

As best shown in Fig. 3, the pumping cylinder 25 is provided with a tubular cylinder liner 37 therein providing longitudinal passages 38 therebetween, the liner having a bore 39 in which is disposed a reciprocable pump piston 40. The motor piston 30 and pump piston 40 are connected by an intermediate piston rod 42 by which reciprocation of the motor piston is communicated to the pump piston. It will be noted that the pilot rod 35, the motor piston 30, the intermediate piston rod 42, and the pump piston 40 are all provided with axial passages 43 which connect with an axial passage 44 in a lower piston rod 45, the lower piston rod being connected to the lower end of the pump piston and extending downwardly therefrom. The purpose of the passages 43 and 44 is to provide fluid communication through the rods 35, 42 and 45 to balance the fluid pressure on the upper and lower ends of the rods as more fully described in my said Patent No. 2,311,157.

The general operation of the fluid operated pump 18 is well known in the art, being described in detail in my aforesaid Patent No. 2,134,174, and needs be described only briefly herein. Operating fluid, such as, for example, clean oil, is supplied under relatively high pressure to the casing head 12 through a supply tubing 46 connected thereto and leading from a suitable source of operating fluid (not shown), and flows downwardly through the operating fluid tubing 19 to the pump 18 to actuate the same. Such operating fluid is alternatively supplied to opposite ends of the motor piston 30 through the passages 28 and 34 to reciprocate the motor piston. Reciprocation of the motor piston 30 operates through the intermediate piston rod 42 to similarly reciprocate the pump piston 40, which is of the double-acting type and draws oil from the reservoir 15 through the pump inlet 47 into the liner 37 of the pump cylinder 25 and expels it therefrom into the production tubing 14 through discharge ports 48. Such pumped oil flows upwardly through the production tubing 14 and through the casing head 12, being discharged therefrom into a discharge tubing 49 through which it is conveyed to a point of use or storage (not shown).

As previously indicated, my shock absorbing piston may be employed as either the motor piston 30 or pump piston 40 of the pump 18, although it will, of course, be understood that I do not intend to be limited to the particular pumping mechanism described heretofore, since the shock absorbing piston may be employed in connection with other suitable pumping structures.

or may be employed in installations other than pumping installations if desired.

The motor piston 30, including features of the invention, is best shown in detail in Fig. 5, and includes an outer tubular piston sleeve 50 provided with annular grooves 51 in which conventional piston rings 52 are retained, the piston rings forming a sliding fluid tight fit with the bore 29 of the motor cylinder liner 27. The ends of the piston sleeve 50 are substantially closed by an upper head 53 and a lower head 54, the heads being suitably threaded into the sleeve, to form a central chamber 55. The upper head 53 is provided with an axial bore 56 through which the pilot rod 35 extends, and the lower head 54 is provided with an axial bore 57 through which the intermediate piston rod 42 extends. The rods 35 and 42 preferably have the same external diameter, and the bores 56 and 57 are sufficiently larger than this diameter to provide clearances 58 and 59, respectively, therebetween, these clearances preferably being in the order of .002 inch or more per inch of diameter of the bores.

Provided in the central chamber 55 is a cylindrical plunger 61 into which the lower end of the pilot rod 35 and the upper end of the intermediate piston rod 42 are suitably threaded, the plunger being of slightly less external diameter than the internal diameter of the central chamber to form a clearance 62 therebetween which is preferably of the same order of magnitude as the clearances 58 and 59. The plunger 61 has an upper end 63 and a lower end 64 and is substantially shorter than the chamber 55, so that when the upper end engages the upper head 53 the lower end will be spaced from the lower head 54, and vice versa. Due to the clearances 58, 59, and 62, the concentricities of the parts of the motor piston 30 do not have to be accurately maintained to provide a free sliding fit in the bore 29, as the parts of the piston may adjust themselves radially, within limits, to compensate for any minor inaccuracies in fabrication.

Assuming that the motor piston 30 and the pump piston 40 are at the upper end of their strokes, as shown in Figs. 2 and 3, pressure is applied to the upper end of the motor piston by the operating fluid to drive the motor piston downwardly. Assuming that gas is present in the liner 37 of the pump cylinder 25 below the pump piston 40, the motor piston 30 will tend to drive the pump piston downwardly very rapidly at a high initial speed, as represented by the portion 70 of the curve shown in Fig. 6, until such gas is compressed and the pump piston strikes solid, or relatively incompressible, fluid, represented by the peak 71 of the curve of Fig. 6. If a conventional piston were used as the motor piston 30, upon the pump piston 40 striking solid fluid both pistons would decelerate substantially instantaneously to produce a deceleration peak of large magnitude and short duration, such as that illustrated by the portion 72 of the curve of Fig. 6, so that the speed of the moving parts of the pumping mechanism would be reduced very quickly from the high initial speed thereof to nearly zero and then increase to a normal operating speed commensurate with the volume of operating fluid supplied to the motor cylinder through ports 33 and 34 and applying pressure to the motor piston 30. Such a rapid deceleration of the motor and pump pistons 30 and 40 may introduce hydraulic shock loads of sufficient intensity to cause considerable damage to the components of the mecha-

nism. It will be apparent that such large accelerations and decelerations of the moving parts of the pumping mechanism 18 may occur whenever the load on the pump piston 40 decreases or increases, respectively, and may be caused by operating the pump beyond the capacity of the well, by operating the pump with inoperative pump valves, or under various other conditions, as well as by operating the pump with oil which contains gas.

Since operating fluid under relatively high pressure is alternately admitted to the opposite ends of the motor piston 30, such fluid will fill the clearances 58, 59, and 62 and the central chamber 55 around the plunger 61, to provide a fluid cushion between the plunger and the heads 53 and 54. As the plunger 61 may move longitudinally relative to the heads 53 and 54, and as the plunger is shorter than the central chamber 55, a lower space 67 may be formed between the lower end 64 of the plunger and the lower head 54, and an upper space 68 may be formed between the upper end 63 of the plunger and the upper head 53 when the plunger is in its lowermost position with its lower end 64 in engagement with the lower head as illustrated.

As illustrated in Fig. 5, the motor piston 30 has just completed an upstroke and is ready to commence its downstroke, and the pump cylinder liner 37 below the pump piston 40 is filled with solid well fluid. Upon the admission of operating fluid under pressure to the upper face 69 of the motor piston 30, such pressure will exert a downward force on the upper head 53 to move it downwardly. The piston rod 42 and plunger 61 will tend to remain stationary, and, consequently, the downward movement of the upper head will build up a fluid pressure in the upper space 68, and will tend to reduce the fluid pressure in the lower space 67. If the liner 37 of the pump cylinder is full of solid fluid below the pump piston 40, such pressure in the upper space 68 will build up immediately to a relatively high value, and as soon as the pressure in the upper space 68 rises above the pressure in the lower space 67 it will cause a flow of fluid from the upper space through the clearance 58 to the upper end of the piston where the pressure is being applied. Fluid will also flow from the upper space 68 through the clearance 62 to the lower space 67. Also, since fluid pressure in the lower space 67 will be lower than the fluid pressure in the motor cylinder below the motor piston 30, fluid will also flow into the lower space 67 from this source. The intermediate piston rod 42 will be held against movement by the pump load exerted on the pump piston 40, and hence the plunger 61 will exert a force opposing the pressure applied to the upper face 69 of the motor piston.

The product of the fluid pressure difference between the spaces 67 and 68 multiplied by the difference between the cross-sectional area of the plunger 61 and the cross-sectional area of the intermediate piston rod 42 must exceed the upward force exerted by the piston rod 42 before that rod will move downwardly. The difference in pressure between the spaces 67 and 68 will depend upon the rate at which fluid pressure is applied to the upper face 69 of the motor piston and to the clearances 58, 59, and 62 between the parts, and upon the viscosity of the operating fluid. Therefore, since such clearances can be readily controlled in manufacture, with a given operating fluid the accel-

eration of the piston rod 42 and the pump piston 40 can be readily controlled.

Leakage of operating fluid through the clearances 58, 59, and 62 will continue as the upper head 53 moves downwardly relative to the plunger 61 until the upper end 63 of the plunger engages the upper head 53, at which time such relative movement stops and the total force of the fluid pressure applied to the upper face 69 will be exerted downwardly on the plunger and hence on the pump piston 40 through the intermediate piston rod 42. Thus, the pump piston 40 will accelerate until it is travelling on its downstroke at the normal pumping speed. Due to the lost motion between the upper head 53 and the plunger 61, however, the full pump load is applied relatively slowly to the motor piston, thus preventing fluid shock on the commencement of the downstroke of the pistons.

In the event that the motor piston starts its downward travel as described above when there is gas in the liner 37 of the pump cylinder 25 below the pump piston 40, the motor piston assembly, consisting of the sleeve 50, heads 53 and 54, and the plunger 61, will move downwardly as a unit because very little downward force is required to move the motor piston when no substantial load is on the pump, and hence very little fluid pressure differential will be created between the spaces 67 and 68, and the rate of leakage therebetween will be small. Therefore, very little if any relative movement between the upper head 53 and the plunger 61 will take place during movement of the motor piston under such a condition of substantially no load. If the liner 37 of the pump cylinder 25 is entirely filled with gas below the pump piston, the motor piston 39 and the pump piston will thus move downwardly together at a rate higher than normal throughout their strokes. If there is some solid fluid in the liner 37 below the pump piston 40, both pistons will still move downwardly together until such gas is compressed and the pump piston strikes the solid fluid, represented by the peak 71 on the curve of Fig. 6, at which time pressure will build up in the upper space 68 and decrease in the lower space 67, and the lost motion will be taken up by the flow of operating fluid through the clearances 57, 58 and 62, as described above, permitting a deceleration of a relatively low magnitude, as illustrated by the portion 73 of the curve of Fig. 6, thus gradually absorbing the increase in pump load and reducing hydraulic shock effects, which are undesirable, as pointed out above. As will be apparent, on the upstroke of the motor piston 39 and pump piston 40, the relative movement of the parts is merely reversed.

From the foregoing it will be understood that by virtue of my invention the cushioning action of the motor piston 39 is substantially the same when the pump piston 40 strikes solid fluid after travelling a substantial distance with no appreciable load as it is upon normal starting when the pump cylinder 25 is filled with solid fluid. Thus, I can provide an effective cushion against hydraulic shock effects occurring at any point in the stroke of the pump piston 40, that point being where full load is applied and where hydraulic shock would otherwise occur.

Although I have disclosed an exemplary embodiment and an illustrative application of my invention, I do not intend to be limited to the specific disclosures contained herein, since my invention is susceptible to other applications and since various changes, modifications, and substi-

tutions may be incorporated in the embodiment disclosed without departing from the spirit of the invention. Consequently, I desire to be afforded the protection offered by the full scope of my appended claims.

I claim as my invention:

1. In a fluid operated pump, the combination of: a motor cylinder; a motor piston in said motor cylinder; a pump cylinder; a pump piston in said pump cylinder, one of said pistons having a movable sleeve element having a chamber therein and having a movable plunger element in said chamber and movable relative to said sleeve element, said plunger element being shorter than said chamber to provide a space therebetween at both ends, said plunger element being of smaller diameter than said chamber so as to provide an annular clearance therebetween connecting said spaces; and piston rod means connecting said plunger element and the other of said pistons.

2. In a fluid operated pump, the combination of: a motor cylinder; a motor piston in said motor cylinder; a pump cylinder; a pump piston in said pump cylinder, one of said pistons having a movable sleeve element having a chamber therein and having a movable plunger element in said chamber and movable relative to said sleeve element, said plunger element being shorter than said chamber to provide a space therebetween at both ends, said plunger element being of smaller diameter than said chamber so as to provide an annular clearance therebetween connecting said spaces, said clearance being approximately 0.002 inch per inch of diameter of said chamber; and piston rod means connecting said plunger element and the other of said pistons.

3. In a fluid operated pump, the combination of: a motor cylinder and a pump cylinder; a pump piston in said pump cylinder; a piston rod connected to said pump piston and extending into said motor cylinder; and a motor piston in said motor cylinder, said motor piston including a sleeve element adapted to provide a close sliding fit with the wall of said motor cylinder, said sleeve element enclosing the end of said piston rod and providing an annular chamber therearound, a plunger disposed in said chamber and rigidly connected at one of its ends to said piston rod, said plunger having a length less than that of said chamber and having an external diameter less than the internal diameter of said chamber so as to provide a first annular clearance therebetween, a pilot rod rigidly connected to the other end of said plunger and extending from said sleeve element, and means substantially closing the ends of said chamber and encircling said rods so as to provide second annular clearances between said means and each of said rods, each of said second annular clearances communicating with said chamber.

4. In a fluid operated pump, the combination of: a motor cylinder and a pump cylinder; a motor piston in said motor cylinder; a piston rod connected to said motor piston and extending into said pump cylinder; and a pump piston in said pump cylinder, said pump piston including a sleeve element adapted to provide a close sliding fit with the wall of said pump cylinder, said sleeve element enclosing the end of said piston rod and providing an annular chamber therearound, a plunger disposed in said chamber and rigidly connected at one of its ends to said piston rod, said plunger having a length less than that of said chamber and having an external diameter less than the internal diameter of said chamber

so as to provide a first annular clearance therebetween, a pilot rod rigidly connected to the other end of said plunger and extending from said sleeve element, and means substantially closing the ends of said chamber and encircling said rods so as to provide second annular clearances between said means and each of said rods, each of said second annular clearances communicating with said chamber.

5. In a fluid operated pump, the combination of: a motor cylinder; a motor piston in said motor cylinder; a pump cylinder; a pump piston in said pump cylinder, one of said pistons being hollow to provide a chamber therein and having a plunger element in said chamber and movable relative to said one piston, said plunger element being shorter than said chamber, said plunger element being of smaller diameter than said chamber so as to provide an annular clearance therebetween throughout the length of said plunger element; and piston rod means connecting said plunger element and the other of said pistons.

6. In a piston means for a fluid operated pump, the combination of: sleeve means adapted to form a fluid-tight sliding fit with the interior of a cylinder; head means rigidly secured to one end of said sleeve means to provide a cylindrical chamber in said piston means; plunger means in said chamber, said plunger means being smaller in diameter than said chamber so as to provide a clearance forming a fluid passage therebetween, said plunger being substantially shorter than said chamber; and rod means extending through said head means into said chamber and connected to said plunger means, said head means having a bore through which said rod means extends, said bore being of greater diameter than said rod means so as to provide a clearance forming a fluid passage therebetween.

7. In a piston means for a fluid operated pump, the combination of: sleeve means adapted to form a fluid-tight sliding fit with the interior of a cylinder; first head means rigidly secured to one end of said sleeve means to provide a cylindrical chamber in said piston means; second head means secured to the other end of said sleeve means; plunger means in said chamber, said plunger means being smaller in diameter than said chamber so as to provide a clearance forming a fluid passage therebetween, said plunger being substantially shorter than said chamber; first rod

means extending through said first head means into said chamber and connected to said plunger means; and second rod means extending through said second head means into said chamber and connected to said plunger means, said head means each having a bore through which said rod means extends, said bore being of greater diameter than said rod means so as to provide a clearance forming a fluid passage therebetween.

8. In a piston means for a fluid operated pump, the combination of: sleeve means adapted to form a fluid-tight sliding fit with the interior of a cylinder; first head means rigidly secured to one end of said sleeve means to provide a cylindrical chamber in said piston means; second head means secured to the other end of said sleeve means; plunger means in said chamber, said plunger means being smaller in diameter than said chamber so as to provide a clearance forming a fluid passage therebetween, said plunger being substantially shorter than said chamber; first rod means extending through said first head means into said chamber and connected to said plunger means; and second rod means extending through said second head means into said chamber and connected to said plunger means, said head means each having a bore through which said rod means extends, said bore being of greater diameter than said rod means so as to provide a clearance forming a fluid passage therebetween, said rod means and said plunger means being tubular in form to provide a continuous fluid passage therethrough.
